UNITED STATES PATENT OFFICE

WILLIAM J. O'CONNOR, OF NEWMARKET, NEW HAMPSHIRE

AUTOMATIC STOP MECHANISM FOR WINDING MACHINES

Application filed December 5, 1929. Serial No. 411,817.

This invention relates to a machine for winding material such as thread or yarn on a core, such as a spool or a bobbin, the core being rotated on its axis to accumulate the material in the form of a circular mass or winding on the core.

The object of the invention is to provide a winding mechanism having simple, durable and effective means operable by the wound mass when the latter acquires a predetermined diameter and yardage, to stop the rotation of the core and hold it at rest, for the removal of the core and its charge from the machine.

15 Of the accompanying drawings forming a part of this specification,—

Figure 1 shows in perspective an embodiment of my invention associated with elements of a well known winding machine.

20 Figure 2 is a section in the plane indicated by the line 2—2 of Figure 1.

Figure 3 is a view similar to Figure 2, showing the machine conditioned to stop the winding operation.

25 Figure 4 shows in perspective one of the elements of the improved automatic mechanism.

Figure 5 is a side view of the other element of the automatic mechanism.

30 Figure 6 is a longitudinal sectional view, showing a core, a winding thereon, and the hereinafter described driven element attached to the core.

Figure 7 is a perspective view, showing a 35 different embodiment of the automatic mechanism.

Figure 8 is a section on the line indicated by 8—8 in Figure 7.

40 The same reference characters indicate the same parts in all of the figures.

Figures 1, 2 and 3 show a winding mechanism adapted to wind a single core. It will be understood that the winding mechanism shown may be a unit of a machine which may include a plurality of said mechanisms. The said machine or unit includes a frame 12, which may be of any suitable construction, whereby it is adapted to support the parts 45 hereinafter described. The representation

of the frame may be considered as conventional.

The machine includes a friction drive composed of a driving element, and a driven element attachable to a core 14 (Figure 6). The 55 driving element is composed of a shaft 15, journaled in bearings 16 fixed to the frame, and friction wheels 17 fixed to the shaft. The driven element, attachable to the core 14, is composed of a cylindrical rod 18, inserted in an axial bore in the core 14, and friction pulleys 19 and 20 fixed to the rod, and clamped against the ends of the core, so that the rod, the pulleys, and the core are adapted to rotate as a single part. The pulley 19 is immovably fixed to the rod 18, and the pulley 20 is provided with an internally threaded bushing 21 (Figure 6) engaged with a threaded portion of the rod and removable therefrom, to permit the removal of the core 70 when a winding 22 has been completed thereon, the operation of screwing the pulley 20 on to the rod causing the clamping of the core between the pulleys 19 and 20. The ends of the rod 18 project from the pulleys and 75 constitute trunnions which are removably inserted in open bearings 23 fixed to the frame. The end of the rod shown at the right in Figure 6 as projecting from the threaded portion of the rod to form a trunnion, should be of slightly smaller diameter than said threaded portion to permit the removal of the core and the driven pulleys.

The core 14 is in this instance, provided with heads 24, between which the winding 80 22 is formed.

The arrangement is such that during the winding operation the pulleys 19 and 20 bear on upper portions of the wheels 17, and the rotation of the driving element causes the 85 rotation of the driven element and the core attached thereto, thus causing a winding to be formed on the core. In a machine which includes a plurality of winding units, the shaft 16 is usually elongated and provided with a plurality of pairs of friction wheels 17.

The construction thus far described is well known and in common use.

The mechanism is characterized by the automatic mechanism next described, operable 100

by a completed winding 22 to shift the driven element and the wound core 14 when the winding 22 acquires a predetermined diameter, and thus break the frictional engagement between the driving wheels 17 and the driven pulleys 19 and 20 to stop the winding operation, and maintain the wound core at rest and in condition for removal from the machine.

- 10 Said mechanism in the preferred embodiment shown by Figures 1 to 6, comprises a fixed upwardly facing track including two spaced apart track members 26, formed on arms 27 of a substantially U-shaped bracket 15 having means such as a shank 28 and bolts 20 cooperating therewith for engagement in a predetermined position with the frame 12, and a cylindrical shiftable lifting pulley 29, having trunnions 30 in rolling contact and 25 frictional engagement with the track members 26. At one end of the track is a stop 25 being formed on the bracket, as best shown by Figure 4. During the winding operation 30 the trunnions 30 normally abut the stop members 31, and arrest the lifting pulley in a starting position as shown by Figures 1 and 2.
- 35 The arrangement is such that when the core winding 22 is completed or acquires a predetermined diameter indicated by the dotted circle in Figure 2, and the full line circle in Figure 3, the periphery of the winding 40 contacts with the lifting pulley 29 and causes the trunnions 30 thereof to roll on the track, to the stop members 32. The core is 45 thereby raised so that the frictional engagement of the driven pulleys with the driving wheels is broken and the lifting pulley 29 is maintained in the shifted position shown by Figure 3, and in contact with the stop members 32, by downward pressure of the thread winding 22 upon it, until an attendant 50 removes the winding.

The downward pressure of the completed thread winding on the lifting pulley 29 causes a sufficient frictional engagement between the trunnions 30 and the track members 26, to cause the described movement of the lifting pulley on the track. Endwise displacement of the lifting pulley is prevented by the arms 27, on which the track members 26 are formed, the ends of the pulley being 55 in close proximity to said arms and track members.

In the embodiment shown by Figures 7 and 8, the trunnions of the lifting pulley 29 are omitted, and said pulley rests on and 60 frictionally engages an upwardly facing track composed of a single member 35, provided at one end with a stop 36, and at its opposite end with a stop 37. Ears 38 are 65 provided between the stops to prevent endwise displacement of the pulley. The shank

28 may be formed on the stop 37. The track member 35 may be the body portion of a metal plate from which the stops 36 and 37, and the ears 38 are bent upward. The downward pressure of the completed thread winding 70 on the lifting pulley 29 causes a sufficient frictional engagement between the periphery of said pulley and the single track member 35, to cause the described movement of the pulley on the track.

75 It will now be seen that each embodiment includes a fixed upwardly facing track located in a predetermined position below the driven element of the winding machine, a lifting pulley supported by the track and movable thereon by traction when rotated, and fixed spaced apart stops at opposite ends of the track, one stop being adapted to cooperate with the track in supporting the pulley in a starting position under the driven element and a winding 22 thereon, to cause the completed winding to contact with and rotate the pulley 29, and thereby cause it to move on the track to the other stop, and at the same time, raise the driven element 80 to stop the winding operation.

85 In each embodiment one of the stops is adapted to cooperate with the track, the pulley, the raised driving element and the winding 90 22 thereon, to maintain the pulley in its raised position until the completed winding is removed from the machine by the attendant.

95 It will be seen that my improved automatic mechanism is extremely simple and is embodied in two parts, one including an upwardly facing track having means for engagement in a predetermined position with the frame 12. The lifting pulley, constituting the other part of the stop motion, may 100 be operatively installed by simply placing it loosely on the track.

105 When the lifting pulley is in its shifted position, shown by Figure 3, and by dotted lines in Figure 8, it is caused to remain in 110 said position by the contact of the winding 22 with its periphery, and when the driven element and the wound core are removed by an attendant from the machine, the lifting pulley is free to return to its starting position 115 shown by Figures 1, 2 and 7, and by full lines in Figure 8. I prefer to incline the tracks as shown by the drawings, so that the stop which arrests the lifting pulley in its shifted position, is higher than the other stop. This 120 inclination causes the pulley to return automatically to its starting position when the winding 22 is removed.

125 I claim:

1. A friction drive winding machine of the character stated, comprising driving friction wheels, driven friction pulleys carrying the core of a thread winding and separable from the driving wheels to stop the rotation of the core, the machine being charac- 130

terized by a stop mechanism including a fixed upwardly facing track, a core-lifting pulley supported by and movable by traction on the track with its periphery spaced from an incomplete thread winding on the core, and in position to be frictionally engaged and rotated by the periphery of a completed winding, the arrangement being such that the lifting pulley is shifted on the track by a completed winding and caused to separate the driven pulleys from the driving wheels, a fixed stop at one end of the track adapted to arrest the lifting pulley in a starting position, and a fixed stop at the opposite end of the track adapted to arrest said pulley in its shifted position.

5 2. A friction drive winding machine as specified by claim 1, the track being inclined to cause the lifting pulley to automatically return to its starting position when the raised

20 thread winding is removed.

3. A friction drive winding machine as specified by claim 1, the track being provided with means for preventing endwise displacement of the lifting pulley.

25 4. A friction drive winding machine as specified by claim 1, the track being composed of two spaced apart track members, and the lifting pulley being provided with trunnions in tractional engagement with the track members, the ends of the lifting pulley being in close proximity to the inner sides of the track members, so that endwise displacement of said pulley is prevented.

30 In testimony whereof I have affixed my signature.

35 WILLIAM J. O'CONNOR.
